M. McCANN

WORK CLAMP FOR BUTTONHOLE SEWING MACHINES

Filed July 8, 1922

UNITED STATES PATENT OFFICE.

MICHAEL McCANN, OF GLENMORRIS, NEW YORK, ASSIGNOR TO FREDERICK OSANN COMPANY, OF NEW YORK, N. Y., A CORPORATION OF NEW YORK.

WORK CLAMP FOR BUTTONHOLE-SEWING MACHINES.

Application filed July 8, 1922. Serial No. 573,650.

To all whom it may concern:

Be it known that I, MICHAEL McCANN, a citizen of the United States of America, residing in Glenmorris, Long Island, in 5 the county of Queens and State of New York, have invented certain new and useful Improvements in Work Clamps for Button-hole-Sewing Machines, of which the following is a true and exact description, reference being had to the accompanying drawings, which form a part thereof.

My invention relates to work clamps for button hole sewing machines and has for its object to provide a clamping device for holding 15 the cloth in which the button hole is to be formed with great security and under the best possible conditions as to stretch for the formation of the button hole.

The nature of my improvements will be 20 best understood as described in connection with the drawings in which they are illustrated and in which

Figure 1 is a side elevation of a portion of a button hole sewing machine including 25 the work holding clamping mechanism.

Figure 2, a cross sectional view on the line 2—2 of Fig. 1.

Figure 3 is a view similar to Fig. 2, but 30 with the clamp mechanism shown closed down in work holding position.

Figure 4 is a longitudinal section on the line 4—4 of Fig. 3.

Figure 5 is a plan view of the needle plate.

Figure 6, a perspective view of the lower 35 clamp member.

Figure 7, a perspective view of the upper clamp member shown in reversed position, and

Figure 8 is a view on the line 8—8 of 40 Fig. 1.

A is the housing or casing of the machine, A' indicating the usual opening through the top plate of the casing for the passage of the needles and A² the overhanging arm of 45 the machine carrying the needles indicated at A³. B is the needle plate of the machine having openings as indicated at B' and B² for the passage of the needles and a longitudinal slot indicated at B³ for the passage of 50 the knife which cuts the button hole and on

each side of the knife slit and needle passages I have formed parallel grooves indicated at B⁴ B⁴. C indicates the clamp holding slide moving, as is common in such machines, in guideways formed on the top of 55 the machine casing, and extending forward from this slide C and over the needle plate. B is the lower clamp member D in which is formed the opening D' over which the portion of the cloth J in which the button hole 60 is to be formed is stretched, and at each end of this opening D' are formed the transverse slots indicated at D² and D³ separated from the opening D' by the cross bars D⁴ D⁴. E is an arm carrying the upper clamp member 65 and pivoted to the slide C as indicated at E', the clamp member indicated at H being preferably carried, as shown, on an elastic arm E² attached to the arm E. The arm E and the clamp member attached to it are 70 normally pressed down with a proper elastic pressure, as shown, by a spring F² surrounding a rod F and resting on the top of the frame E, the tension of the spring being adjusted by a nut indicated at F'. The 75 frame E and the upper clamp member can be raised by any convenient mechanism. As shown, a rod G attached to the under side of the arm E extends through a slit in the top plate of the machine casing into operative registry with the finger G³ secured at one end of the lever G' pivoted at G² and having an end G⁴ which extends through an opening in the side of the casing and is usually connected by a chain with a treadle. 80

The upper clamp member H is formed with a central opening H' to expose the portion of the cloth J in which the button hole is to be formed and on each side of this opening I provide downwardly extending bars indicated at H² H² placed so as to enter the opening D' in the member D in fairly close relationship to the edges of this opening and preferably and, as shown, to extend down into the grooves B⁴ of the 85 needle plate. At the end of the opening H' I form downwardly extending bars H³, H³, placed so as to enter the opening D' in fairly close relationship to the cross bars D⁴ and I also provide the upper clamp member with 90 95 100

downwardly extending cross bars H^4 , H^4 , located so as to register with and extend down into the slots D^2 , D^3 , and by preference, bars H^2 , H^3 and H^4 are serrated so as to 5 take a better grip on the cloth.

In operation, the upper clamp member being in elevated position and the lower clamp member resting on the needle plate, as shown in Figures 1 and 2, the cloth is 10 inserted between the upper and lower clamp members and the upper clamp member permitted to move downward with the result that the longitudinal bars H^2 press the cloth down over the side edges of the opening D' 15 in the lower clamp member and preferably into the grooves B^4 in the needle plate with the result that the cloth is, during the action of cutting and sewing a button hole, firmly pressed on the needle plate; at the same time 20 the cross bars H^3 , H^3 press the cloth down on to the needle plate and over the ends of the opening D' and the cross bars H^4 , H^4 , press a bight of the cloth down into the grooves D^2 , D^3 , with the result, as is of 25 course obvious, that the cloth is very positively and rigidly held between the clamp members at each end of the portion in which the button hole is to be formed and also firmly pressed against the needle plate over 30 which it is moved by the clamp.

The advantages of my improved clamping mechanism will be readily recognized by all skilled in the art and while I believe that the construction illustrated and above described is the best form in which my invention can be embodied it will be quite obvious that certain features of my new and improved clamp can be used with advantage apart from others. I do not wish to 35 be understood as limiting my claims to the specific construction except in so far as the different features thereof are expressly called for in the claims.

Having now described my invention, what 40 I claim as new and desired to secure by Letters Patent, is:

1. A work clamp for button hole sewing machines comprising a lower member having a recess over which the portion of 45 the cloth in which the button hole is to be formed extends, two parallel cross bars one at each end of said recess and slots formed in the member outside of said bars in combination with an upper clamp centrally recessed to expose the goods and having 50 downwardly extending bars adapted to enter the slots in the lower member.

2. A work clamp for button hole sewing machines comprising a lower member having a recess over which the portion of the cloth in which the button hole is to be 55 formed extends, two parallel cross bars one at each end of said recess and slots formed in the member outside of said bars in combination with an upper clamp centrally re-

cessed to expose the goods and having downwardly extending bars adapted to enter the slots and the ends of the recess in the lower member and longitudinally lying downwardly extending bars arranged to pass into 60 the recess in the lower member along its sides.

3. A work clamp for button hole sewing machines comprising a lower member having a recess over which the portion of the cloth in which the button hole is to be formed extends, two parallel cross bars one at each end of said recess and slots formed in the member outside of said bars, in combination with an upper clamp centrally recessed to expose the goods and having transversely lying downwardly extending bars adapted to enter the slots in the lower member.

4. A work clamp for button hole sewing machines comprising a lower member having a recess over which the portion of the cloth in which the button hole is to be formed extends, two parallel cross bars one at each end of said recess and slots formed in the member outside of said bars, in combination with an upper clamp centrally recessed to expose the goods and having transversely lying downwardly extending bars adapted to enter the slots and the ends of the recess in the lower member.

5. A work clamp for button hole sewing machines comprising a needle plate having parallel grooves formed in its upper face, in combination with a lower clamp member moving backward and forward over the needle plate in a line parallel to the grooves and formed with a recess over which the portion of the cloth in which the button hole is to be formed extends and an upper clamp member recessed to expose the cloth and having longitudinal bars extending down along the sides of the recess in the lower member into the grooves in the needle plate.

6. A work clamp for button hole sewing machines comprising a needle plate having parallel grooves formed in its upper face, in combination with a lower clamp member moving backward and forward over the needle plate in a line parallel to the grooves and formed with a recess over which the portion of the cloth in which the button hole is to be formed extends and with transversely extending slots separated from the recess by cross bars, and an upper clamp member recessed to expose the cloth and having transverse bars extending down into the slots and longitudinal bars extending down along the sides of the recess in the lower member into the grooves in the needle plate.

7. A work clamp for button hole sewing machines comprising a needle plate having parallel grooves formed in its upper face, in combination with a lower clamp

member moving backward and forward over the needle plate in a line parallel to the grooves and formed with a recess over which the portion of the cloth in which the button hole is to be formed extends and with transversely extending slots separated from the recess by cross bars and an upper clamp

member recessed to expose the cloth and having transverse bars extending down on each side of the cross bars and longitudinal bars extending down along the sides of the recess in the lower member into the grooves in the needle plate.

10 MICHAEL McCANN.
